UNITED STATES PATENT OFFICE.

JOSIAH LUCUS JONES, OF ST. PETERSBURG, FLORIDA.

MELTED-ICE-WATER COOLER.

Application filed August 19, 1927. Serial No. 214,140.

This invention relates to improvements in water coolers such as are used in the homes, schools, churches, theaters, city halls and office buildings, and more particularly to a type in which ice is used exclusively for drinking purposes as it melts.

The principal object of the invention is to provide for a water cooler of the type aforesaid, and one of extremely simple and inexpensive construction, such as will be convenient and satisfactory for use in the aforesaid places, particularly in those sections of the country where the available supply of drinking water is of questionable pureness and artificial ice can be depended upon to furnish pure water as it melts.

Another object of the invention is to provide a water cooler of the type set forth in the form of a cabinet of any convenient size wherein the ice and water compartment is placed in the upper half of said cabinet, and the lower half of said cabinet is used for the purpose of housing a drain bucket and a receptacle to hold the used paper cups and other refuse.

A further object is that a provision is made for a space around the ice and water compartment in which insulating material may be placed or removed as desired to regulate the melting of the ice to suit the convenience of the operator.

With the foregoing and other objects in view, the invention resides in the certain new and useful combination, construction and arrangement of parts as will be more fully described, set forth in the appended claim, and illustrated in the accompanying drawings in which;

Fig. 1 is a cross section of the invention viewed from the side, and

Fig. 2 is a cross section of the invention viewed from the front.

Referring to the drawings, wherein similar characters of reference designate corresponding parts throughout the several views thereof, and as shown therein comprises an outer case A, which is made in the form of a cabinet of any suitable material and of any convenient size. In the top of said case is a sub-frame F to which is attached the flanged top end of water and ice compartment B and forms a support for same, and both the ice compartment B and the outer case A are closed at the top by hinged closure M. Spaced just beneath ice compartment B is a V-shaped transverse partition dividing

outer case A into an upper and lower compartment. Said partition is covered with sheet metal and directly in the center over waste bucket C a hole is cut to allow any moisture caused by sweating of compartment B to fall into waste bucket C. At or near the bottom of outer case A is a sub-floor P that supports waste bucket C, and there are two openings in the front lower half of outer case A that are normally closed by double doors—(openings and doors not shown)—that are provided to allow for ready access to lower half of outer case A for the purpose of emptying waste bucket C and used paper cup receptacle D.

Compartment B is constructed of sheet metal of a kind suitable for housing a supply of ice and drinking water. It is made in rectangular shape to conform with outer case A and has its top end flanged out to attach to and rest upon sub-frame F. The bottom of compartment B is made to slope from the side walls to a transverse center and at the front lowermost part a water spigot H is attached which passes outwardly through the outer case A. Just beneath sub-frame F and extending downwardly all around compartment B suitable spaces E E E E are provided for the purpose of placing insulating material to control the melting of the ice in compartment B.

Made fast to and becoming a part of the right hand lower door that normally closes lower half of outer case A is a used paper cup receptacle D, the front side of said receptacle extends outwardly through said door in a semi-funnel shape and the opening thus formed is normally closed by trap lid L which is hinged to the door at top of said opening, and on the inside attached to trap lid L is a weight which causes said lid to automatically close after being pushed open to receive a used cup or other refuse.

A drain receptacle K is attached to the front wall of outer case A just beneath the water spigot H and a drain pipe attached thereto extends inwardly through outer case A and downwardly to a point conveniently over waste bucket C as illustrated in Fig. 1.

In the use of this form of the invention, artificial or manufactured ice which contains one pint of water to every pound of ice and which is always practically pure, is placed in compartment B and allowed to melt, and as needed is drawn off through spigot H for drinking. In case ice melts too fast com-

partment B may be lifted out and insulating material be placed in the provided spaces E E E E, or in case the ice does not melt fast enough all of the insulating material in spaces E E E E may be removed, and further the cake of ice in compartment B may be chipped up with an ice pick. Ice once pure cannot be contaminated until it melts. Any drippage from spigot H is 5 caught by receptacle K and drained into waste bucket C. Used paper cups are placed in receptacle D by pressing down on trap lid L. In this manner all unsightly waste buckets and used paper cup receptacles are 10 conveniently hid within the lower half of outer case A.

Without further description it is thought that the features and advantages of this invention will be readily apparent to those 15 skilled in the art of manufacturing same,

and it will of course be understood that changes in the form, proportion and minor details of construction may be resorted to without departing from the spirit of the invention or its scope as claimed.

25

Having fully described the invention, what is claimed, is:

A melted-ice-water cooler comprising an outer casing, a V-shaped transverse partition in said casing dividing it into an upper and lower compartment, a removable water cooler in the upper compartment and having a V-shaped bottom, said cooler being spaced from the walls of said casing and said partition, a faucet attached to the lower part of 30 said tank and extending through the front walls of said casing, a drain beneath said faucet leading to a receptacle within said casing.
